RAILWAY TRAFFIC CONTROLLING
APPARATUS

Lowell B. Yarbrough, Decatur, Ill., assignor to
The Union Switch & Signal Company, Swiss-
vale, Pa., a corporation of Pennsylvania

Application March 3, 1936, Serial No. 66,811

11 Claims. (Cl. 246—22)

My invention relates to railway traffic controlling apparatus, and particularly to signaling apparatus for governing the movement of traffic over stretches of single track over which traffic moves in both directions.

I will describe two forms of apparatus embodying my invention, and will then point out the novel features thereof in claims.

In the accompanying drawings, Figs. 1A, 1B and 1C, when placed end to end in order with Fig. 1A at the left, constitute a diagrammatic view showing apparatus embodying one form of my invention applied to that portion of a single track railroad located between and including the ends of two adjacent passing sidings, while Figs. 1A and 1C placed end to end in the reverse order, that is, with Fig. 1A at the right of Fig. 1C, form a diagrammatic view showing the apparatus of my invention applied to the double track portion of the railroad which includes the siding situated between two adjacent single track stretches. Fig. 2 illustrates a modification of a portion of the apparatus of Fig. 1B, having to do with the approach lighting of the signals and also embodying my invention.

One object of my invention is the provision of a novel absolute-permissive block signaling system, in which the signals for both directions are controlled over circuits employing but two line wires, and in which the relative polarity of the current supplied to the line circuit at one end or the other may be reversed to provide three-position control of the signals for both directions. A feature of my invention is the provision, in a system of this character, of means for preventing short circuits when two current sources are connected to the opposite ends of the same line circuit in such direction that their effects are additive.

Another object of my invention is the provision of an improved system of directional control for the single track stretch, which operates upon the approach of a train towards a signal that has been cleared, to maintain the established traffic direction until the train vacates the stretch.

A further object of my invention is the provision of improved means for lighting the signals upon the approach of a train, which operates in such a manner as to render the signal visible when the train is at a greater distance than heretofore without the use of additional line wires.

Other objects and purposes of my invention will be made apparent as the description proceeds.

In order to simplify the drawings and to enable the circuits to be more readily traced, I have herein identified each switch and signal by a number and each relay by a letter or combination of letters with a distinguishing prefix identifying the switch or signal with which the relay is associated. The various relay contacts are identified by numbers and those contacts not adjacent the respective relays which operate them bear the reference characters for the respective relays as well as the numbers identifying the contacts. Furthermore, instead of showing the sources of current for energizing the various line and local circuits and the wires leading thereto in detail, I have shown only the terminals of the sources, which I have designated by the reference characters B and C, referring to the power supply and common return terminals, respectively. It is to be understood that in accordance with the usual practice, a separate local source of current is provided at each location, for each direction.

Referring to the drawings, the references 1 and 1^a designate the track rails of the main track of a single track railway over which traffic may move in either direction, the track rails being divided into sections by insulated joints 2, each section being provided with a track circuit identified by the reference character T with a distinguishing prefix. Each track circuit is provided with the usual track battery 3 and with a track relay identified by the reference TR with a prefix corresponding to that of the associated track circuit. Power-operated track switches 5 and 7 connect the two ends of a non-track circuited passing siding PS with the main track, and the movement of traffic over these switches is governed by signals bearing the references 6 and 8, respectively, each signal being identified by a distinguishing prefix. The head block signals RA6 and RC6 govern traffic moving from left to right on the main track or from the siding, respectively, over switch 5 into the adjacent single track stretch, and considering the drawings 1A, 1B and 1C to be arranged end-to-end in that order, it is to be noted that the control limit of these signals, as far as opposing traffic is concerned, extends to the opposing head block signals LA8 and LC8 which are similarly arranged to govern traffic moving from right to left over the same territory. The spacing of trains moving in the same direction through the single track stretch is governed by the intermediate signals 12 and 10, or by signals 11 and 13, of Fig. 55

1B, depending upon the direction of movement, as will be apparent from the drawings.

Considering now that Fig. 1A is placed to the right of Fig. 1C so as to further extend the territory illustrated it will be noted that signal RA8 governs traffic moving from left to right on the main track of the double track portion, and that its control limit, as far as opposing traffic is concerned, extends to the corresponding opposing signal LA6 when switch 5 is normal, but only to signal RA6 which is then at stop, when switch 5 is reversed to permit an opposing train to enter the siding. The circuits are symmetrically arranged with respect to the two directions, and the control limit of signal LA6 similarly extends to signal RA8 when switch 7 is normal and to signal LA8, then at stop, when switch 7 is reversed. Signals RB8 and LB6 are slow speed signals governing the movement of traffic into the siding, and their control limits extend only to the ends of the corresponding switch section.

It is to be understood that each of the track switches and the associated group of signals of Figs. 1A and 1C are subject to manual control from a remote point, such as a dispatcher's office, through the medium of a centralized traffic control system. To illustrate such control in its relation to the present invention, considering Fig. 1A for example, (that shown in Fig. 1C being similar) a dotted line connection is shown extending from a switch machine 5W for controlling switch 5 to a two-position switch lever SW and also to two switch indication relays 5NWP and 5RWP, and it is to be understood that in accordance with the usual practice that when lever SW occupies position N, as shown, switch 5 is operated to normal, relay 5NWP is energized and relay 5RWP deenergized, as shown, but that when lever SW occupies position R, switch 5 is reversed, relay 5RWP is energized and relay 5NWP deenergized. The manual control of the signals is effected by energizing one or the other of a pair of signal control relays which are identified by the reference HS with distinguishing prefix, such, for example, as the relays R6HS and L6HS of Fig. 1A, and as illustrative of the manual control of the signals, dotted line connections are shown from these relays to a three-position signal lever bearing the legend "Sig" and a reference number. It is to be understood that when lever 6, for example, is in its mid-position as shown, the signals identified by the same number are at stop, but when the lever occupies position L or R, relay L6HS or R6HS will be energized to clear one of the associated signals 6, subject to control by traffic conditions and in accordance with the position of the track switch and the condition of the opposing signals, to permit a traffic movement toward the left or right, respectively, over the associated track switch.

Each of the signals is illustrated as of the searchlight type, such for example as that disclosed in the Reissue Patent No. 14,940, granted to Eli J. Blake on August 31, 1920. Each signal mechanism bears the reference M with a prefix similar to the designation of the corresponding signal, and each mechanism including a three-position circuit controller. It is to be understood that when the winding of a signal mechanism is energized by current of one relative polarity, front contact G and back contact Y of its circuit controller are closed, as illustrated for example by mechanism 11M, as shown, and the signal then displays a green light indicating clear or proceed; that when the winding is energized by

current of the opposite relative polarity, front contact Y and back contact G of the circuit controller are closed, as illustrated for example by mechanism 13M, as shown, and the signal then displays a yellow light indicating caution; and that when the winding is deenergized both back contacts are closed, as illustrated by the remaining mechanisms, as shown, and the signal then displays a red light, indicating stop. Each signal is electrically lighted by a lamp E which is energized continuously in the case of the manually controlled signals, while the intermediate signals are lighted only upon the approach of a train, as will be hereinafter explained.

Each signal mechanism controls a repeating relay bearing the reference H with a prefix identifying the corresponding signal, which relay is energized when the signal indicates proceed or caution and serves to control the energization of the next signal in the rear for the same direction. Each relay H associated with a head-block signal is of the slow-release type, while each relay H associated with an intermediate signal is a slow pickup slow release relay, as indicated conventionally on the drawings by transverse arrows applied to the contacts of these relays. A directional stick relay designated by the reference S with identifying prefix, is associated with each relay H controlled by the intermediate signals of Fig. 1B. These relays serve to provide the so-called absolute-permissive feature of the scheme of control, and operate in such a manner that when a train enters the single track stretch all signals for the opposing direction are held at stop until the entire stretch is vacated, while the signals for the same direction are caused to successively indicate caution and proceed in the rear of a moving train so as to permit following trains to enter the single track stretch and to properly space the movement of these trains through the stretch.

It is to be understood that switch locking means, not shown in detail, is provided to prevent operation of the track switches except when conditions are proper. The switch locking means includes a pair of approach locking stick relays, one for each direction for each switch, which relays are identified in the drawings by the general reference LS. Considering the approach locking stick relay R6LS, for example, (the scheme of control for the remaining relays LS being similar), it is to be understood that switch machine 5W is locked against operation unless relay R6LS is energized, that relay R6LS is energized only when a signal indication relay R6RP is energized, and that the latter relay is energized only when the home signals RC6 and RA6 for the corresponding direction indicate stop and the distant signal, which is signal RA8 in this instance, indicates stop or caution. Furthermore, if signal RC6 or RA6 is put to stop manually, the energization of relay R6LS may be delayed for a time interval following the energization of relay R6RP by the operation of a time element relay 5TE, which relay is checked to insure that it occupies its normal position when the signals are put to stop by including a back contact thereof in the signal control circuits. This control of the approach locking relays LS by the signal indication relays RP is indicated by a dotted line connection between these relays, and may be arranged as disclosed in Fig. 2 of Patent No. 1,952,072, granted May 15, 1934, to H. A. Wallace, for Railway traffic controlling apparatus. Although the switch locking forms no part of the

present invention, the approach locking relays are shown herein because front contacts of the relays LS for each direction are included in the control circuits for the signals for the opposite direction, as will be pointed out hereinafter, and these relays not only control the switch but also serve to prevent clearing of two opposing signals at the same time and safeguard the reversal of traffic if a signal is put to stop in the face of an approaching train.

Since the relative polarity of the current supplied to the line circuits for the control of the signals is reversible, and since the same line wires are used for the control of the signals for both directions, it may happen that current sources may be connected at opposite ends of the same line wires in such direction that their effects are additive. To prevent excessive flow of current under this condition, I include a series relay identified by the general reference Z in each line circuit where this may occur. Each relay Z is adjusted to be non-responsive to the normal line current due to the voltage of a single source and to pick up only under the double voltage condition mentioned, in which case the relay will open its back contact to include a resistor 14 in the line circuit so as to reduce the current to a safe value, but not enough to release the relay Z as long as it is energized by the two sources in series.

As illustrated in the drawings, the apparatus is shown in the condition which it assumes following a train movement from right to left, all of the head block signals being at stop. The intermediate signals are not lighted, although mechanism 13M is energized in the caution position and mechanism 11M in the clear position. The relays which repeat the stop indication of the "A" signals, such as relay RA6RP, are energized. The circuits for all such relays shown are similar, and that for the one referred to may be traced from terminal B, back contacts G and Y of the circuit controller of mechanism RA6M, relay RA6RP to terminal C. The signal indication relays such as R6RP are also energized. The circuit for R6RP, for example, may be traced from terminal B, back contact G of the circuit controller for signal RA8, wire 15, front contact 16 of relay RA6RP, back contacts G and Y of the circuit controller for signal RC6, relay R6RP to terminal C. Relay R6RP being energized, the approach locking relay R6LS is likewise energized, as indicated on the drawings, and each of the remaining relays LS are also energized. The winding of the mechanism for signal 13 is energized over a circuit which may be traced from terminal B, back contact 17 and winding of relay 13Z, back contact 18 of relay LA6H, front contact 19 of relay R6LS, back contact 20 of relay R6HS, front contacts 21 and 22 of track relays 5TR and 4TR, line wire 23, front contact 24 of track relay 13TR, back contacts 25 and 26 of relays 12H and 12S, winding of mechanism 13M, back contacts 27 and 28 of relays 12S and 12H, front contact 29 of relay 13TR, line wire 30, contacts 31 and 32 of relays 4TR and 5TR, back contact 33 of relay R6HS, front contact 34 of relay R6LS, back contact 35 of relay LA6H, to terminal C. Mechanism 13M is energized in the caution direction over the circuit just traced, but relay 13Z remains in its deenergized position. Relay 13H is now energized over a circuit which may be traced from terminal B, back contact G and front contact Y of mechanism 13M, front contact 36 of relay 12TR, relay 13H to terminal

C. The energization of relay 13H completes a circuit which may be traced from terminal B, back contacts G and Y of 12M, front contact 37 of relay 13H, contact 38 of track relay 12TR, line wire 39, contact 40 of track relay 11TR, back contacts 41 and 42 of relays 10H and 10S, winding of mechanism 11M, contacts 43, 44, 45, line wire 46, contacts 47 and 48 to terminal C. Mechanism 11M is energized in the clear direction over this circuit.

Assuming now with the apparatus as shown that the operator desires to effect a train movement from section 6T through the single track stretch from left to right, and that signal lever 6 is moved to position R to energize relay R6HS, lever SW for switch 7 being in position N. The energization of relay R6HS opens back contacts 20 and 33 in the circuit for 13M, thereby causing this mechanism to assume the stop position, de-energizing relay 13H. When relay 13H releases it opens contacts 37 and 48 in the circuit for 11M, which assumes the stop position, deenergizing relay 11H. When relay 11H releases it completes a circuit for 10M which may be traced from terminal B, back contact 49 and winding of relay 10Z, back contact 50 of relay RA8H, front contact 51 of relay L8LS, back contact 52 of relay L8HS, front contacts 53 and 54 of relays 7TR and 9TR, line wire 55, front contact 56 of relay 10TR, back contacts 57 and 58 of relays 11H and 11S, winding of 10M, contacts 59, 60, 61, line wire 62, contacts 63, 64, 65, 66, 67 to terminal C. Mechanism 10M is now energized in the caution direction, completing a circuit for relay 10H similar to that already traced for relay 13H, and relay 10H when energized completes a circuit for 12M which may be traced from terminal B, back contacts G and Y of 11M, front contacts 41 and 40 of relays 10H and 11TR, line wire 39, front contact 38 of relay 12TR, back contacts 37 and 68 of 40 relays 13H and 13S, winding of relay 12M, contacts 69, 48, 47, line wire 46, front contacts 45 and 44 to terminal C. Mechanism 12M is now energized in the proceed direction, completing the circuit for relay 12H, and relay 12H when energized completes a circuit for RA6M, which may be traced from terminal B, back contacts G and Y of mechanism 13M, front contacts 25 and 24 of relays 12H and 13TR, line wire 23, front contacts 22, 21, 20 and 70 of relays 4TR, 5TR, R6HS and L6RP, back contact 71 of relay L6HS, front contact 72 of relay 5TR, back contact 73 of relay 5TE, front contacts 74 and 75 of relays R6HS and 5NWP, winding of relay RA6M, front contacts 76, 33, 32, 31, line wire 30, front contacts 29 and 28 to terminal C. Signal RA6 now indicates proceed, relay RA6H becomes energized and relay RA6RP is deenergized. The release of the latter relay causes relays R6RP and R6RS to release in sequence, and relay R6RS when released locks switch 5 and also opens contact 71 in the circuits for controlling signals LA6 and LB6 and contacts 19 and 34 in the circuit for controlling signal 13.

Assuming next with the apparatus as shown that the operator desires to effect a train movement from siding PS through the single track stretch from left to right, and that signal lever 6 is moved to position R after switch 5 has been reversed in response to a movement of lever SW to position R. The several operations which result from the energization of relay R6HS now take place as already described in connection with the clearing of signal RA6, except that since relay 5NWP is now deenergized, mechanism 75

RA6M is disconnected from front contacts 74 and 33 of relay R6HS. However, relay 5RWP is now energized and connects these contacts to mechanism RC6M over front contacts 78 and 79, so that RC6M is energized in place of RA6M. It will be apparent from the drawings that the circuit for controlling signal RC6 is otherwise identical with that for signal RA6, and that mechanism RC6M when energized likewise releases relays R6RP and R6LS to lock switch 5 and the opposing signals. It follows, therefore, that signal RA6 or RC6, dependent upon the position of switch 5, can be cleared only when all opposing signals up to and including signals LA8 and LC8 are at stop, and all track sections between signal RA6 and RA8 at stop are unoccupied.

I will now assume that a train moving from left to right accepts signal RA6 or RC6 and passes through the single track stretch. When the train enters section 5T, track relay 5TR releases to open contacts 72, 21 and 32 in the signal control circuit to put the signal to stop. It is to be understood that relay R6HS also releases and that the operator restores lever 6 to normal. Signals RA6 and RC6 will therefore remain at stop until lever 6 is again operated. As the train proceeds, track relays 4TR and 13TR release successively, the apparatus of Fig. 1A again assuming the condition shown as soon as the train vacates sections 5T and 4T. When the train enters section 13T, the release of track relay 13TR completes the lighting circuit for signal 12 which extends from terminal B, back contact 80 of relay 13TR, lamp 12E, back contact 86 of relay 13S to terminal C. Mechanism 12M being energized in the proceed position, the lighting of lamp 12E causes signal 12 to display a proceed indication to the approaching train.

At the same time, contact 81 of relay 13TR drops to open the circuit for relay 12H and to complete a circuit for the directional stick relay 12S, which may be traced from terminal B, front contact G of mechanism 12M, back contact 81 of relay 13TR, front contact 82 of relay 12H, back contacts 83 and 84 of relays 13S and 13H, relay 12S to terminal C, whereupon relay 12S picks up, completing a temporary stick circuit from terminal B, front contact G of 12M, back contact 81 of relay 13TR, front contact 85 and winding of relay 12S to terminal C. As hereinbefore mentioned, relay 12H is a slow pickup, slow-release relay, and when it releases a second stick circuit for relay 12S is closed which extends from terminal B, back contact 82 of relay 12H, front contact 85 and winding of relay 12S to terminal C. It follows, therefore, that relay 12S remains picked up as long as relay 12H remains deenergized, that is, as long as section 13T is occupied or signal 12 remains at stop.

It is to be noted that the pickup circuit for relay 12S includes back contacts 83 and 84 of the corresponding relays 13S and 13H for the opposite direction and that the circuit for relay 13S is similar to that for relay 12S and includes back contacts 87 and 88 of relays 12S and 12H. The two relays 12S and 13S are therefore fully checked so that but one direction of traffic can be set up at a time.

One purpose of the directional stick relays S is to provide directional control of the approach lighting circuits for the intermediate signals. Thus lamp 12E is lighted when a train approaching signal 12 enters section 13T, as already described, but not when a train moving in the oppo-

site direction enters section 13T, because then relay 13S will be energized and will open the circuit for lamp 12E at its back contact 86. Another purpose of the directional stick relays S is to supply current of reverse polarity to the line circuit for the next signal in the rear. Thus when relay 12H releases closing back contacts 25 and 28, front contacts 26 and 27 of relay 12S supply current of reverse polarity to line wires 23 and 30 included in the control circuit for signals RA6 and RC6, as soon as the train vacates section 13T and relay 13TR picks up. However, in the case described it has been assumed that relay R6HS has been released, and it follows that this line circuit now includes a current source at each end and that these sources are connected in the additive direction. This circuit may be traced from terminal B of the source adjacent signal 13, back contacts G and Y of 13M, front contact 27 of relay 12S, thence as already described over line wire 30, to back contact 35 of relay LA6H, terminal C of the source adjacent signal LA6, through this course to its terminal B, back contact 17 and winding of relay 13A, back contact 18 of relay LA6H, thence over line wire 23, front contact 26 of relay 12S to terminal C of the first-mentioned source. Relay 13Z picks up under this condition and by opening back contact 17 inserts a current limiting device as illustrated by the resistor 14 in the line circuit so as to prevent an excessive flow of current. This overload condition exists only when relay 1S is energized, but when relay 12H is energized to supply current of normal polarity to the line circuit the sources at the two ends are in opposition so that substantially no current will flow and relay 13Z is not operated.

If, now, with relay 12S energized, the operator reenergizes relay R6HS to permit a following train to enter the stretch, the control circuit for signal RA6 or RC6 as already described will be re-established, except that in this case the polarity will be reversed. It follows that signal RA6 or RC6 will indicate caution if relay R6HS is operated when a train moving from left to right has vacated section 13T and signal 12 is at stop.

Assuming now that the train continues through section 12T and enters 11T, the release of 11TR will complete a circuit for lamp 10E causing signal 10 to display a caution indication to the approaching train, because, as already pointed out, 10M is energized in the caution direction, and relay 10S will be picked up and relay 10H released in a manner similar to that described for the corresponding relays associated with signal 12. It follows that mechanism 12M will become energized in the caution direction by current of reverse polarity supplied over front contacts 42, 43 of relay 10S as soon as the train vacates section 11T to permit relay 11TR to pick up. When 12M becomes energized, relay 12H again picks up, breaking the stick circuit for relay 12S so that relay 12S releases. Current of normal polarity is now supplied over front contacts 25 and 28 of relay 12H to energize RA6 or RB6 in the clear direction, so that signal RA6 or RB6 will also indicate proceed, providing relay R6HS is energized.

I will next assume that the operator reverses switch 7 and moves lever 8 to the right to energize relay R8HS, in order to route the train moving from left to right in the single track stretch into the siding at the right of section 11T. With switch 7 reversed, it is to be understood that relay 7NWP is released and 7RWP is energized. With relay R8HS energized the circuit for RB8M is closed, and may be traced from terminal B, front

contact 89 of relay 7RWP, back contact 90 of relay 7NWP, front contact 91 of relay L8LS, back contact 92 of relay L8HS, front contact 93 of relay 7TR, back contact 94 of relay 7TE, front contacts 95 and 96 of relays R8HS and 7RWP, winding of RB8M to terminal C. When RB8M is energized, signal RB8 indicates caution, or slow speed, and relays R8RP and R8LS are released to lock switch 7 and the opposing signals. The distant signal 10 remains at caution when signal RB8 is energized.

Considering for the moment that the operator had energized relay R8HS with switch 7 normal to clear signal RA8, relay RA8H will become energized and its contacts 50 and 67 will reverse the polarity of the current supplied to 10M. It follows that signal 10 will display a proceed indication to an approaching train only in the event switch 7 is normal and signal RA8 indicates caution or clear.

Assuming now that the train moving from left to right passes signal RB8 or RA8, when the train enters 7T, track relay 7TR releases to open contact 93 to restore the signal to stop. When the train vacates section 9T, mechanism 10M will become energized in the caution direction, because relay RA8H is deenergized, energizing relay 10H and releasing relay 10S, and current of normal polarity will be supplied to line wires 39 and 46 to energize mechanism 12M in the proceed direction. The apparatus of Fig. 1B will then be in a condition similar to that shown except that the direction of energization of the line circuits is reversed. Thus considering the block comprising the track sections 11T and 12T, the right-hand leaving signal 10 is energized in the caution direction in place of the similar left-hand signal 13, as shown, and the entering signal 12 is energized in the proceed direction in place of the similar signal 11, as shown.

I will next assume that with Figs. 1A and 1B placed at the right of Fig. 1C to further extend the territory illustrated, and with switch 7 reversed to permit trains moving from left to right to enter siding PS, that the operator moves lever 6 to position L with switch 5 normal, to energize relay L6HS to permit a train moving from right to left to pass on the main track. The train or trains on the siding obviously will be held there by signal RC6 until the opposing train vacates section 5T and switch 5 is restored to normal, the circuits for controlling signal RC6 already having been described in detail. Signal LA8 is at stop because switch 7 is reversed, and when the operator energizes relay L6HS a circuit for energizing LA6M is closed which may be traced from terminal B, back contact 97 of relay LA8H, front contacts 98 and 99 of relays 7RWP and 8TR, line wire 100, front contacts 101, 102, 103, and 104 of relays 6TR, L6HS, 5NWP and 5TR, winding of 60 LA6M, front contacts 105, 71 and 72 of relays 5NWP, L6HS and 5TR, back contacts 73 and 74 of relays 5TE and R6HS, front contacts 77, 106, 107 and 108 of relays R6LS, 5NWP, L6HS and 6TR, line wire 109, front contacts 110 and 111 of relays 8TR and 7RWP, back contact 112 of relay LA8H to terminal C. Relay LA8H being deenergized, signal LA6 is energized to indicate caution, causing relay LA6H to be energized to reverse the polarity of the current supplied to its distant signal 13 as already explained in connection with the similarly arranged signals RA8 and 10 for the opposite direction.

After the trains moving toward the right into siding PS vacate section 7T, signal RB8 may be

held at stop by restoring lever 8 to normal to release relay R8HS. Switch 7 may then be restored to normal, whereupon the operator may move signal lever 8 to position L to energize relay L8HS to clear signal LA8.

The circuits for controlling signal LA8 are similar to those for the corresponding signal RA6 already described, as is apparent from the drawings, and therefore these circuits will not be traced in detail. Since relay R8HS is released before the switch is operated, contact 98 of relay 7RWP in the circuit for clearing signal LA6 becomes shunted by a branch circuit including back contact 113 of relay R8HS and contacts 114 and 115 of relays 7TR and R8LS, while contact 111 of relay 7RWP is shunted by a similar branch including contacts 116, 117 and 118, as soon as section 7T is vacated and the locking for switch 7 is released, so that the circuit for LA6M is not interrupted when switch 7 is restored to normal and relay 7RWP thereby deenergized.

When signal LA8 assumes the caution or proceed position, relay LA8H becomes energized and its contacts 97 and 112 reverse the polarity of the current supplied to LA6M to cause the indication of signal LA6 to change from caution to proceed.

Assume now that with relay LA8H energized, that the operator restores signal LA6 to stop by releasing relay L6HS, the terminals B and C of the source adjacent signal LA8 will then be connected to the left-hand ends of line wires 109 and 100, respectively, over front contacts 112 and 97 of relay LA8H, while the terminals C and B of the source adjacent signal RA6 will be connected to the right-hand ends of these line wires in such a direction that the effects of the two sources are additive. Thus a connection will be made from terminal B of the source adjacent signal RA6 over back contact 119 and winding of relay R8Z, contacts 120, 121, 122, 102 and 101 to line wire 100, and thence over front contact 97 to terminal C of the source adjacent signal LA8, through this source to its terminal B, and thence over front contact 112 to line wire 109, and from line wire 109 over contacts 108, 107, 123, 124 and 125 to terminal C of the first-named source. Relay R8Z will therefore pick up, and by opening back contact 119 will introduce a resistor 14 into the line circuit so as to prevent an excessive flow of current under this condition. It is evident that this condition exists only when relay LA8H is energized, and that when this circuit is in the condition shown in the drawings the sources at the two ends are in opposition so that substantially no current will flow and relay R8Z not be operated.

It is readily apparent from the drawings that in arranging a meet as hereinbefore described, the operator could have as well routed the trains moving from left to right over the main track and routed the opposing train through the siding, since the circuits are symmetrically arranged for both directions. In such case the operator would have cleared the slow speed signal LB6 over circuits similar to those already described for the similar signal RB8, and would have energized a control circuit for signal RA8 that is the same as that already described for the opposing signal LA6, except that the control circuit for signal RA8 includes the series relay R8Z, which relay however remains in its released position and is not operated by the current for energizing RA8M.

In systems of this character, it is usually desir-

able to provide approach control of the lighting of the intermediate signals as hereinbefore described, in the interest of economy of current, but if the train speeds are high and their stopping distances are relatively great, or if the block sections are short it may be desirable to cause the signals to become lighted when the approaching train is at a greater distance than that provided by arrangement of Fig. 1B. In order to extend this distance, but without the use of additional line wires, I propose to modify the circuits of Fig. 1B by including the apparatus of Fig. 2 for controlling the connections of the track batteries to the track rails. It is to be understood that Fig. 2 may be substituted for the corresponding portion of the block including track sections 11T and 12T, and that similar arrangements may be provided for the other blocks. Referring to Fig. 2, a series relay 11A or 12A is included in the connection between the track rails and track battery 3 for the two adjacent sections 11T and 12T, and each relay 11A or 12A when energized operates a contact 126 or 127 to disconnect the track battery 3 and to shunt the track circuit including the other relay.

The relays 11A and 12A are non-responsive to the current which operates the respective track relays 11TR and 12TR but pick up due to the increased flow of current resulting from the shunting of the track relay by the wheels and axles of a train occupying the section. It follows that when a train moving from left to right passes signal 12, relay 12TR will be shunted and relay 12A will be operated, and contact 127 will then disconnect battery 3 from and will short circuit the rails of section 11T to cause 11TR to release also, so as to close its back contact 128 to light lamp 10E. Signal 10 will therefore become lighted when the approaching train enters section 12T instead of when the train enters section 11T, thereby substantially doubling the distance available for stopping the train in the event the signal indicates stop.

It also follows that when relays A are used, relay 10S will become energized when the train approaching signal 10 enters section 12T rather than when it enters section 11T, but this is without significance, and the apparatus in its modified form as illustrated by Fig. 2 operates generally in the same manner as in the case of the form hereinbefore described in detail.

Although I have herein shown and described only two forms of apparatus embodying my invention, it is understood that various changes and modifications may be made therein within the scope of the appended claims without departing from the spirit and scope of my invention.

Having thus described my invention, what I claim is:

- 60 1. In combination, a stretch of railway track comprising two adjoining track sections each having a track relay, said relays being situated at opposite ends of the stretch, signals at the ends of the stretch each distinctively operable in accordance with the polarity of the current supplied thereto for governing the movement of traffic in opposite directions through the stretch, a reversible line circuit comprising two line wires extending from one end of the stretch to the other for controlling the signals, said circuit including front contacts of said track relays, switching means at each end of the stretch operable to connect either the adjacent signal or a source of current of a given relative polarity to the line circuit at that end, and means con-

trolled by each said switching means in response to the deenergization of the track relay at the same end of the stretch for connecting a source of current of the reverse polarity to the line circuit at that end.

2. In a signaling system for railroads, a stretch of track comprising a block section over which traffic moves in both directions, an entering signal and a leaving signal at each end of the stretch, a reversible line circuit comprising two line wires extending from one entering signal to the other for controlling said entering signals in accordance with traffic conditions in said stretch, means for each leaving signal for clearing such signal effective only if the adjacent entering signal is at stop, and means controlled by each leaving signal when cleared and by a train occupying the stretch and approaching said signal for energizing said line circuit at the end adjacent said leaving signal to cause the entering signal at the opposite end of the stretch to indicate caution when the stretch is vacated by said train.

3. In a signaling system for railroads, a stretch of track comprising a block section over which traffic moves in both directions, an entering signal and a leaving signal at each end of the stretch, a reversible line circuit comprising two line wires extending from one entering signal to the other for controlling said entering signals in accordance with traffic conditions in said stretch, means for each leaving signal for clearing such signal effective only if the adjacent entering signal is at stop, means controlled by each leaving signal when cleared and by a train occupying the stretch and approaching said signal for energizing said line circuit by current of a given relative polarity at the end adjacent said leaving signal to cause the entering signal at the opposite end of the stretch to indicate caution when the stretch is vacated by said train, and means controlled by each leaving signal effective if said signal is cleared when said stretch is unoccupied for energizing said line circuit by current of the opposite relative polarity to cause such entering signal to indicate proceed.

4. In combination, a stretch of railway track comprising a block section, signals at the ends of the stretch each distinctively operable in accordance with the polarity of the current supplied thereto for governing the movement of traffic in opposite directions through the stretch, a source of current at each end of the stretch, a reversible line circuit comprising two line wires extending from one end of the stretch to the other for controlling the signals in accordance with traffic conditions in the stretch, switching means at each end of the stretch independently operable to connect either the adjacent signal or source of current to said line circuit at that end, means at each end of the line circuit for reversing the polarity of the current supplied thereto, a relay connected in series with the source at one end which responds only when the source at the other end of the line circuit is connected thereto in the additive direction, and means controlled by said relay for reducing the flow of current in said line circuit when both of said sources are connected thereto.

5. In combination, a reversible line circuit comprising two line wires, a source of current and an electroresponsive device selectively responsive to the polarity of the current supplied thereto at each end of said line circuit, switching means at each end of the line circuit independently

- operable to connect either the adjacent source or electroresponsive device to said line circuit at that end, means at each end of the line circuit for reversing the polarity of the current supplied thereto, a relay connected in series with the source at one end, and means controlled by said relay for limiting the flow of current when the two sources are connected to the line circuit in the additive direction.
6. In combination, a reversible line circuit comprising two line wires, a source of current and an electroresponsive device selectively responsive to the polarity of the current supplied thereto at each end of said line circuit, switching means at each end of the line circuit independently operable to connect either the adjacent source or electroresponsive device to said line circuit at that end, means at each end of the line circuit for reversing the polarity of the current supplied thereto, a current limiting device, a relay at one end of the line circuit which responds to the current in said line circuit only when the two sources are connected thereto in the additive direction, and means controlled by said relay when energized for including said current limiting device in said line circuit in series with the source adjacent said relay.
7. In a signaling system for railroads, a stretch of railway track over which traffic moves in both directions and comprising two adjoining track sections, a track relay for each section, one track relay being located at each end of the stretch, signals at the ends of the stretch for governing the movement of traffic in opposite directions out of the stretch, a lighting circuit for each signal, means for closing each lighting circuit including a back contact of the track relay at the same end of the stretch, and means responsive to the shunting of the other track relay by a train at the remote end of the stretch for releasing said first named track relay.
8. In a signaling system for railroads, a stretch of railway track over which traffic moves in both directions, comprising two adjoining track sections, a track relay for each section, one being located at each end of the stretch, a source of current for each track section, an auxiliary relay in series with each said source, and means controlled by each said auxiliary relay in response to the occupancy of the corresponding track section for opening the track circuit for the other track section, a signal at each end of the stretch for governing the movement of traffic out of the stretch, a lighting circuit for each signal, and means including a back contact of each track relay for controlling the lighting circuit for the signal at that end of the stretch.
9. In combination, a stretch of track comprising two adjoining track sections, a track circuit for each section including a track relay connected across the track rails, one track relay being located at each end of the stretch, a source of current for each track section located at the junction of said sections, for energizing said track relays; two auxiliary relays, one being connected across the track rails of each section in series with the source of current for such section, and means controlled by each auxiliary relay in response to the occupancy of the corresponding track section by a train for releasing the track relay for the other section, comprising contacts of such auxiliary relay included in the connection to the track rails of the source of current for the other track section.
10. In a signaling system for railroads, a stretch of railway track comprising a block section over which traffic moves in both directions, electrically controlled entering and leaving signals at each end of the stretch, a reversible line circuit extending from one entering signal to the other and controlled by traffic conditions in said stretch, a slow pickup slow release repeating relay for each signal, means controlled in accordance with traffic conditions for selectively energizing the leaving signal at one end of the stretch or the other, a circuit closed by each signal when energized for energizing the associated repeating relay, means effective when the repeating relay is energized to disconnect the adjacent entering signal from the line circuit and to then connect a source of current to the line circuit at that end to energize the entering signal at the other end over said line circuit, and means effective when the repeating relay for either entering signal becomes energized for preventing the energization of the adjacent leaving signal.
11. In a signaling system for railroads, a stretch of track comprising a block section over which traffic moves in both directions, electrically controlled entering and leaving signals at the ends of the stretch, each adapted to indicate stop, caution, or proceed, a reversible polarized line circuit extending from one entering signal to the other and controlled by traffic conditions in said stretch, means for selectively energizing the leaving signal at one end of the stretch or the other to cause such signal to indicate caution or proceed, a slow pickup slow release repeating relay for each leaving signal, a circuit closed when a leaving signal indicates caution or proceed for energizing the associated repeating relay provided a portion at least of said block section is not occupied, means rendered effective when a repeating relay becomes energized to disconnect the adjacent entering signal from the line circuit and to then connect a source of current of a given relative polarity to the line circuit at that end to cause the entering signal at the other end of the stretch to indicate proceed, and direction selecting means rendered effective when a train governed by said signals vacates said stretch to supply current of the opposite relative polarity to said line circuit to cause said last named entering signal to indicate caution.

LOWELL B. YARBROUGH.
